(57) **CLAIM**

The ornamental design for a magnetic fence pipe plumb level, as shown and described.

DESCRIPTION

FIG. 1 is a side elevation showing a first embodiment of our new design for a magnetic fence pipe plumb level, the opposite side being a mirror image thereof;

FIG. 2 is a perspective view thereof;

FIG. 3 is a bottom plan view thereof;

FIG. 4 is a top plan view thereof;

FIG. 5 is an end view thereof showing an inset magnet;

FIG. 6 is an end view opposite that shown in (FIG. 5);

FIG. 7 is a side elevation showing a second embodiment of our new design, the opposite side being a mirror image thereof;

FIG. 8 is a perspective view thereof;

FIG. 9 is a bottom plan view thereof;

FIG. 10 is a top plan view thereof;

FIG. 11 is an end view thereof showing an inset magnet;

FIG. 12 is an end view opposite that shown in (FIG. 11);

FIG. 13 is a side elevation showing a third embodiment of our new design, the opposite side being a mirror image thereof;

FIG. 14 is a perspective view thereof;

FIG. 15 is a bottom plan view thereof;

FIG. 16 is a top plan view thereof;

FIG. 17 is an end view thereof showing an inset magnet;

FIG. 18 is an end view opposite that shown in (FIG. 17);

FIG. 19 is a side elevation showing a fourth embodiment of our new design, the opposite side being a mirror image thereof;

FIG. 20 is a perspective view thereof;

FIG. 21 is a bottom plan view thereof;

FIG. 22 is a top plan view thereof;

FIG. 23 is an end view thereof showing an inset magnet; and,

FIG. 24 is an end view opposite that shown in (FIG. 23);

(Continued)

The broken lines showing portions of the article form no part of the claimed design.

1 Claim, 4 Drawing Sheets
